OIL BURNER

John William Newbery and John Gilbert Newbery, Rockville Center, N. Y., assignors of one-half to Nathan Hirsch, New York, N. Y.

Application November 26, 1932, Serial No. 644,516

2 Claims. (Cl. 158—87)

This invention relates to oil burners, and has particularly to do with oil burners in which the oil is vaporized to commingle with air to give a high combustion without the necessity of employing wicks of any character.

An object of the invention is to provide a burner of this character with an improved arrangement of horizontal and vertical baffles, and an improved combination and arrangement of perforated walls separating the baffles from the base of the burner whereby a high efficiency is assured.

A further object is to provide the base of the burner with removable troughs so that when the troughs become filled or partially filled they may be removed and replaced.

With these and other objects in view, the invention consists in certain novel features of construction and combinations and arrangements of parts, all of which will be more fully hereinafter described and pointed out in the claims.

In the accompanying drawings—

Figure 1 is a view in central longitudinal section illustrating my improved burner;

Figure 2 is a top plan view partially broken away to illustrate the parts below;

Figure 3 is a view in side elevation of one of our improved baffle members and portions of the vertical baffles broken away;

Figure 4 is a view in transverse section on the line 4—4 of Figure 1;

Figure 5 is a view in transverse section on the line 5—5 of Figure 1;

Figure 6 illustrates in perspective the removable troughs which we employ in the base;

Figure 7 is a fragmentary plan view of the base illustrating a modified form of coupling the troughs in the base; and

Figure 8 is a view in section on the line 8—8 of Figure 7.

Our improved burner includes a base A, three superimposed or pyramided baffles, indicated generally by the reference characters B, C and D, and a series of concentric perforated cylindrical walls 1, 2, 3 and 4, supported on the base A and supporting the baffles above referred to.

The base A has a central opening 5, the said base being in reality a ring the upper surface of which is formed with circular grooves 6 and 7, and in these grooves 6 and 7 we locate our improved removable troughs 8. These troughs 8 have outwardly flaring flanges 9 at their upper edges which rest upon shoulders 10 at the upper ends of the grooves 6 and 7, and the walls 1, 2, 3 and 4 above referred to rest directly upon the

flanges 9 of the troughs 8, and fit within the upper portions of the grooved base and insure a snug, tight juncture of parts but which, of course, are capable of separation to remove and replace the troughs in the event that the latter become 60 filled or partially filled. This is one of the important features of our invention.

It is to be understood that the troughs 8 are to be made of any metal or composition or alloy which would best serve under the conditions, 65 and it is obvious that by providing removable troughs instead of subjecting the base to the direct contact of the oil, which is usually hydrocarbon, it is not necessary to replace the base but only the troughs, and this is a simple, inexpensive 70 matter.

11 represents an oil inlet in the base A, with which a supply pipe 12 communicates, and this oil inlet 11 communicates with a pair of spouts 13 extending in opposite directions and discharging downwardly into the troughs 8. A simple construction is to bore the base so that these spouts 13 may be threaded therein for convenient removal. The invention, of course, is not limited to the exact manner although we believe a feed 75 into the top of the troughs is a preferable arrangement.

As a modification of this idea, attention is called to Figures 7 and 8 of the drawings, in which troughs 8 have openings in their bottoms, with 80 tubular screws 14 extended through the bottom of the troughs and coupled to a supply pipe 15, so that in this modified form the oil will be supplied into the bottom of the troughs. This 85 is merely illustrative of the fact that we do not 90 wish to be limited to the exact manner of feeding the oil into the troughs.

The base A is provided with openings 16 so that air may pass upwardly between the walls 2 and 3, as well as into the center of the burner within 95 the wall 1, so that this space between the walls 2 and 3 constitutes an air chamber into which air passes and commingles through the perforated walls with the vapor from the troughs for combustion. The inner wall 1 is appreciably higher or longer than the other walls, and the walls 2 and 3 are of the same height but shorter than the wall 1 and higher or longer than the wall 4.

The baffle B, above referred to, has an annular 105 enlargement 17 which fits into the space at the top of the air chamber formed between the walls 2 and 3, and this baffle B rests directly upon these walls 2 and 3 and has a central opening 18 appreciably larger in diameter than the diameter 110

of the wall 1, so that air and products of combustion may pass freely through this opening; furthermore, the annular enlargement 17 is formed in its lower face with inclined recesses 19 so that products of combustion passing upwardly through the walls 2 and 3 may escape laterally and outwardly; furthermore, this baffle B has openings 20 in line with the space between the walls 3 and 4, and hence while this baffle exercises its function as a baffle it does not interfere with the upward travel of the products of combustion.

The baffle B supports a series of vertical baffles 21 which project downwardly into the space between the walls 2 and 3, and these vertical baffles 21 may constitute integral portions of the baffle B or they may be separate members supported removably, as may be desired. These vertical baffles 21 are of a diameter and of an area sufficient to insure a maximum of radiation of heat thereof to aid combustion. The baffle B is formed on its upper face with radial webs 22 which support the baffle C above referred to. This baffle C is also supported directly upon the upper end 25 of the wall 1 and is formed with a circular groove 23 to receive the wall. This baffle C has a central opening 24, and around this central opening 24 a series of vertical baffles 25, corresponding to the baffles 21, are located. These vertical baffles 25 extend into the central chamber within the central wall 1 and are of such size and proportions as to give the best results.

The invention is, of course, not limited to the specific shapes of the different baffles as these may be varied, but it is desirable that the baffles have a large amount of heat radiating surface in their arrangement of both vertical and horizontal baffles, and hence it is desirable that the horizontal baffles have passage-ways or openings 35 suitably arranged for the passage of the gases, and in Figure 2 I illustrate a form of baffle design, which is efficient.

The baffle D above referred to is supported on top of the baffle C and has a central enlargement 45 26 which fits within the center of the baffle C. The main portion of this baffle D rests upon the baffle C and is formed with webs 27 and openings 28 in any suitable or desired arrangement. In any event, this baffle D extends outwardly above the baffle C and constitutes a deflector and heat radiating medium. The arrangement of webs 29 on the baffle C and openings 30 in the baffle C co-operate with the arrangement of openings and webs and baffles to insure a free circulation, yet 55 offers the maximum of heat radiation for best combustion.

It will thus be noted that our improved burner has a novel arrangement of superimposed pyra-

mided horizontal baffles above the combustion and commingling chambers formed by the walls, 1, 2, 3 and 4, so that as these vapors or gases pass upwardly they come in contact with a large number of metal baffled portions of the burner, which insures a complete combustion. 0

Our improved burner is not only of extreme efficiency and utility but it can be readily assembled and taken apart as occasion may require. This is important as a burner of this kind must be kept clean; furthermore, by providing the removable troughs we not only make it possible to lengthen the life of the base but can insure clean troughs even where it is necessary to remove and replace them, as the cost of the troughs is trifling as compared with the cost of the base and the difficulty in removing or supplying a new base. 85

Of course, we do not wish to be limited in the particular material employed in the manufacture 90 of the troughs, but we believe chromium or other heat resisting metal in sheet form is the best obtainable.

As above stated, while we believe the preferable arrangement is to feed oil into the tops of 100 these troughs, it is obvious that their supply of oil may be regulated in various ways, and a separate supply may be had to each or communication may be had between them.

While we have illustrated what we believe to 105 be the preferred embodiment of our invention, it is obvious that various slight changes may be made with regard to the form and arrangement of parts without departing from our invention, and hence we do not limit ourselves to the precise details set forth but consider ourselves at liberty to make such changes and alterations as fairly fall within the spirit and scope of the claims. 110

What we claim is:

1. An oil burner including a base having a circular groove therein, an oil-receiving removable trough supported on the base and fitting in the said groove in the base, lateral flanges at the edges of the trough, and spaced concentric perforated walls supported on the base and resting on the flanges of the trough. 115

2. An oil burner including a base having a circular groove therein, an oil-receiving removable trough supported on the base and fitting in the said groove in the base, lateral flanges at the edges of the trough, spaced concentric perforated walls supported on the base and resting on the flanges of the trough, and a baffle resting on top of the walls and having vertical baffles extending between the walls. 120 125 130
